SECTIONAL SOFA OR LIKE FURNITURE

Moses Kaufer, New York, N. Y.

Application June 10, 1936, Serial No. 84,400

4 Claims. (Cl. 155—112)

This invention relates to furnitures and has for its main object to provide a furniture which is built up of sections so that said sections may be used individually as separate pieces of furniture or they may assemble in a combination so as to provide the original furniture of which they are the sections.

My invention particularly relates to the usual large and heavy sofas and aims to provide a sofa which is built up of three parts, said parts being adapted to be used individually as chairs, or to be combined into the original sofa, as desired, easily available means being provided for connecting and securing together the sections or for disconnecting them.

It is well known to those versed in this art that many sofas are very large in dimension and heavy in weight so that sometimes they are awkward or even impossible to be placed in a certain room and they give trouble in moving them in or out of certain places where the doors are narrow and they give similar troubles in storing or forwarding them.

My invention aims to remedy this difficulty very often met by people who do not know how to use a heavy sofa in a new place and by movers and storage warehouses when they have to move such a sofa or when they have to store the same, and I divide such sofa into three parts so that the same may be easily and quickly transformed into three chairs, usable separately, each of said chairs again being adapted to be transformed into a bed and their combination into a sofa being also adapted to be transformed into a larger bed.

It will be seen that such a sofa may be easily moved in or out of any place, transferred or stored in a similar manner, and may be placed and used as one unit where the space permits it and where it is so desired, but its individual parts may be separately used in various arrangements and formations to fit it to the room in question, and my section sofa will be also adapted to be transformed into a large bed for one or more persons, or into several smaller or medium beds for children.

Other objects of my invention will be apparent as this specification proceeds, and among others I may mention: to provide a device as hereinbefore characterized which will be simple in construction, attractive in appearance, easily applicable to sofas, couches or other similar furnitures as at present used and constructed, and which will be inexpensive, easy and quick in op-

eration and wherein the constructional elements may be attractively concealed.

In the drawings forming a part of this specification and accompanying the same:

Fig. 1 is a perspective view of a sofa constructed according to my invention in an assembled position, portions of its covering and ornaments having been broken away to indicate the parts and their securing to one another;

Figs. 2, 3 and 4 are perspective views, respectively, of the left hand, right hand and center or middle chairs into which said sofa may be separated;

Fig. 5 is a perspective view showing the method for transforming said sofa, or any part thereof, into a bed;

Fig. 6 is a diagrammatic rear view of my sofa showing means whereby the backs of the parts may be secured to one another, while

Fig. 6a is a sectional detail of such securing means, the section being taken on the line 6a—6a in Fig. 6;

Fig. 7 is a fragmentary diagrammatical detail of the rear of my sofa indicating another method for securing the backs of the various parts to one another;

Fig. 8 is an end view of a section of my sofa showing the securing means between the same and the adjacent other section, while

Fig. 9 is a sectional detail on a larger scale, the section being taken on the line 9—9 of Fig. 8;

Figs. 10 and 11 are perspective views showing a modified form of a middle section of my sofa with swingable arm rests applied thereto, and

Fig. 12 is a diagrammatical fragmentary detail showing a modified embodiment of such an arm rest.

Referring now to the drawings more closely, by characters of reference, the numeral 20 indicates a sofa made according to my invention, in general, having a seat 21, a back 22, a right hand arm rest 23, and a left hand arm rest 24. My sofa is divided into three parts, being a right hand end section 25, a left hand end section 27, and a middle section 26, each section being independent from the other but being adapted to be assembled and fitted to one another, as shown in Fig. 1, to form a sofa 20 and each section having an independent seat and back, designated, for the respective sections, by the numerals 28, 29 and 30, and 31, 32 and 33.

When it is desired the said sections may be taken apart and used individually, forming a right sided arm chair, as shown in Fig. 2, being

the original left hand end section, a left sided one sided arm chair, shown in Fig. 3, being the right hand end section when assembled, and an ordinary upholstered chair, shown in Fig. 4, and being the center section 26 of my sofa when said individual chairs are assembled, as in Fig. 1.

It will be obvious that when the sofa is to be moved into or out of a certain room, its moving will be greatly facilitated on account the same being separated into the sections shown in Figs. 2, 3 and 4, and the same is true when the sofa is being transported or stored. Indeed, as has been mentioned hereinbefore, in some cases a sofa, as shown in Fig. 1, could not be moved at all into or out of some room, or with great difficulties only through a window or the like. Dividing a sofa into such chairs, will also be of great aid in case the space does not allow the use of the sofa as a unit, or if such a use thereof will be awkward and unseemly, in which case the chairs may be arranged in various attractive, artistic groups.

When the sections of my sofa are assembled into a unit, I use means to secure them to one another; and one embodiment of such means is shown in Figs. 8 and 9. Supposing that in said figures, the securing of the left hand section 26 to the middle section 27 is indicated, I secure on the middle section two hook devices 34 and 35, having forwardly projecting upwardly open receiving portions 36 and 37, and I secure oppositely placed axial registering adjacent similar hook devices 38 and 39 on the adjacent end surface 40 of the left hand end section 27. A forward pivoted arm 41 is secured on the end surface 42 of the middle section 26, in alignment with the upper open portion 36 of the hook device 34, and a similar but rearward pivoted arm 43 is secured to the rear thereof in alignment therewith and with the rear hook device 37, the two arms or levers 41 and 43 being interconnected by a yielding slot and pin engagement, as indicated at 44. When the two sections 26 and 27 are placed in alignment with one another, their end surfaces 40 and 42 facing each other, the forward end 45 of the lever 41 will be pushed downwardly, as indicated by the arrow 46, thereby locking the upper ends of the hooks 34 and 38 to one another, as will be obvious, and at the same time the rear portion of the arm or 41 will act through the slot and pin joint 44 on the rearward arm or lever 43 and causes its rearward end 47 to lock the upper ends of the rear hooks 35 and 39 to one another, as it is shown by full lines in Fig. 8.

When it is desired to detach sections 26 and 27 from one another, the forward end 45 will be pushed upwardly so that lever 41 will disengage the hooks 34 and 38, at the same time causing the rear end 47 of lever 43 to move upwardly and to disengage the hooks, as indicated by the dotted

It will be seen that I provided a simple but reliable means for securing the sections of the sofa to one another or for disengaging them, which means may be operated in the front of the narrow slot or opening remaining between the sections of the sofa, as indicated at 48 in Figs. 1 and 9, which slot normally may be covered and concealed by any appropriate draping or ornament adapted to be raised when the locking or unlocking of the sections is desired.

Means will also naturally be provided to ornament the end surfaces of the sections, when they are separated from one another and to conceal the securing means thereon, and one such means

I indicate in Figs. 8 and 9, being simply a loose down-hanging ornament or draping 48 which may be folded and tucked between the upper portions of the sections, as indicated in Fig. 9, when the sections are locked to one another.

Means may also be provided to transform my sofa, or any section thereof, into a bed, and such means, and the appearance of my sofa or a section thereof when transformed into a bed, are shown in Fig. 5. In the simplest form of such means, the upper seat portions 28, 29 and 30 of the sections of my sofa are hinged to suitable lower portions or supports thereof, as indicated by the numeral 50 for the left end section of my sofa, the inner surfaces of said seat sections being formed like resilient mattresses as is well known in this art. When these upper portions of the seats are opened, as shown in full lines for the left hand section of the sofa and in dotted lines for the middle and right hand sections thereof, legs 51 will automatically open to support the outer ends of the beds so formed, as it also is well known in this art, such legs normally being concealed in respective slots or openings 52 in the upper sections of the seats. It will be seen that by this method I may transform the whole sofa into one large bed for two or three persons, or I may transform the individual sections or any two of them into smaller beds, when they may be used independently, suitable for one person, or for children.

For an additional securing of the sections to one another, I may employ locking means between the backs of the sections, as indicated in Fig. 6, said means comprising, a loop device 53 secured 35 on the back of one section, and a similar device 54 secured on the back of the neighboring section above said first loop device 53, the outer loops proper 53a and 54a of said devices being in registering coaxial relation, and then a sliding 40 locking bolt or strip 55 may be pushed through both loops proper 53 and 54, as shown. When it is desired to disengage the sections, said bolt 55 may be removed, and I also preferably apply two pairs of loop devices 53 and 54, on the backs of 45 each pair of sections, operated by one sliding bolt 55. The construction of this securing device also naturally may be concealed by suitable ornaments, draperies or covering.

In Fig. 7 I indicate another simple construction for securing the backs of the sections to one another, consisting of a pivoted hook 58 secured on one section, and a catch or pin 57 to receive the same, secured on the other section. 50

In Figs. 10 to 12, I, finally, show a modified form for the middle section of my sofa, in which arm rest members, 58, pivoted as at 59, may be used as portions of the back 32 of said section, and may be thrown upwardly to merge with the back, as shown in Fig. 10, when said section is used as part of the sofa, or as an independent chair without arm rests, or they may be thrown downwardly to a limit support 60, as shown in Fig. 11, when the chair is independently used and such arm rests are desired. 65

In Fig. 12 I indicate in a fragmentary, dia-
grammatical manner, a modification of such
arm rests, wherein an appropriately formed plate
61 may be secured on the side of the back 32 of
the section in an appropriately concealed man-
ner, the arm rest 58 being adapted to engage and
be supported by the various portions of the front
edge 62 of the plate 61, when the arm rest is
thrown upwardly or downwardly, into its two
desired positions, as will be understood. It is 75
70

also obvious that such arm rests may be used on the free ends of the end sections 25 and 27 also in an entirely similar manner.

While I have shown the preferred embodiment and application of my invention, it will be understood that changes and variations may be resorted to in the construction, combination, details and applications thereof and I reserve my rights to all such changes and variations which 10 are within the spirit of this specification and the scope of the appended claims.

What I claim as new, is:

1. A sofa, comprising a right-hand, a left-hand, and a middle section, entirely separate 15 from one another, an upholstered seat and an upholstered back on each section, the three sections being adapted to be placed together to form the sofa, having the seat and the back of uniform artistic design, formed of the seats and backs of the said three sections; an upholstered stationary end rest adjacent the outer side of each end section and normally concealed means on the meeting surfaces of said sections to removably secure them together; said meeting surfaces having down hanging curtains to normally conceal said securing means but being adapted 25 to be uncovered from over said securing means to permit their operation.

2. A sofa, comprising a right-hand, a left-hand, and a middle section, entirely separate 30 from one another, an upholstered seat and an upholstered back on each section, the three sections being adapted to be placed together to form the sofa, having the seat and the back of uniform artistic design, formed of the seats and backs of the said three sections; an upholstered stationary end rest adjacent the outer side of each end section and normally concealed means on the meeting surfaces of said sections to removably 35 secure them together; said middle section having pivoted arm rests at both sides of its back, normally merging into the design of said back, but being adapted to swing downwardly and to form arm rests so as to fashion said middle section as an 40 armchair; said securing means comprising two pivoted interlocked arms on the outer vertical surface of one section and receiving hooks on the outer surfaces of both adjacent sections, one arm having a forward extension whereby to 45 rock the same, its rocking causing the other arm to rock and said rocking in one direction placing the arms in the respective hooks, and securing said sections together, while the rocking of said arms in the other direction is adapted to release them from said hooks to free said sections from one another.

3. A sofa, comprising a right-hand, a left-hand and a middle section, entirely separate from one another, an upholstered seat and an upholstered back on each section, the three sections being adapted to be placed together to form 50 the sofa, having the seat and the back of uniform

artistic design, formed of the seats and backs of the said three sections; an upholstered stationary end rest adjacent the outer side of each end section and normally concealed means on the meeting surfaces of said sections to removably 5 secure them together; said securing means comprising two pivoted interlocked arms on the outer vertical surface of one section and receiving hooks on the outer surfaces of both adjacent sections, one arm having a forward extension 10 whereby to rock the same, its rocking causing the other arm to rock and said rocking in one direction placing the arms in the respective hooks, and securing said sections together, while the rocking of said arms in the other direction is 15 adapted to release them from said hooks to free said sections from one another.

4. A sofa, comprising a right-hand, a left-hand, and a middle section, entirely separate 20 from one another, an upholstered seat and an upholstered back on each section, the three sections being adapted to be placed together to form the sofa, having the seat and the back of uniform artistic design, formed of the seats and backs of the said three sections; an upholstered stationary end rest adjacent the outer side of each end section and normally concealed means on the meeting surfaces of said sections to removably 25 secure them together; said meeting surfaces having down hanging curtains to normally conceal 30 said securing means but being adapted to be uncovered from over said securing means to permit their operation; said middle section having pivoted arm rests at both sides of its back, normally merging into the design of said back, but 35 being adapted to swing downwardly and to form arm rests so as to fashion said middle section as an armchair; said securing means comprising two pivoted interlocked arms on the outer vertical 40 surface of one section and receiving hooks on the outer surfaces of both adjacent sections, one arm having a forward extension whereby to rock the same, its rocking causing the other arm to rock and said rocking in one direction placing the arms in the respective hooks, and securing 45 said sections together, while the rocking of said arms in the other direction is adapted to release them from said hooks to free said sections from one another.

MOSES KAUFER. 50
